DESIGN FOR A TOOL BOX

William B. Johnson, United States Army

Application September 30, 1941, Serial No. 103,584

Term of patent 3½ years

To all whom it may concern:

Be it known that I, William B. Johnson, Quartermaster Corps, United States Army, Holabird Quartermaster Depot, Baltimore, Maryland, a citizen of the United States, have invented a new, original, and ornamental Design for a Tool Box, of which the following is a specification, reference being had to the accompanying drawing, forming part thereof.

The drawing is a perspective view of a tool box, showing my new design.

The side and end not shown are substantially the same in appearance as the side and end shown in the drawing.

The characterizing features of my design for the tool box shown reside in the specific pair of identical hinged cover portions, provided with hinged handles, all as shown.

I claim:

The ornamental design for a tool box, as shown and described.

WILLIAM B. JOHNSON.
